CHARLES R. MINER, OF SAN FRANCISCO, CALIFORNIA, ASSIGNOR OF ONE-FOURTH TO
MIKE TAMBOR, OF SAN FRANCISCO, CALIFORNIA

MUFFLER FOR INTERNAL COMBUSTION ENGINES

Application filed January 23, 1930. Serial No. 422,759.

The invention relates to mufflers for use with internal combustion engines, and has as its object to provide means for drawing into the muffler air from the outside atmosphere, heating the air within the muffler and thoroughly mixing it with the exhaust gases, thereby producing a mixture which is lighter than the cold air and which will therefore rise and become thoroughly diffused with the atmosphere, thus preventing carbon monoxide poisoning. Moreover, the heated air combines readily with the carbon monoxide, both within the muffler and after passing from the same, thus producing carbon dioxide, which is non-poisonous.

The present invention attains the above object in a simple and efficient manner, without the use of chemicals. The device is inexpensive and entirely automatic in its operation.

The invention will be more readily understood by reference to the accompanying drawings setting forth a simple embodiment of the invention.

In the drawings:

Fig. 1 is a central longitudinal section through the improved muffler, the exhaust pipe from the engine and the exhaust from the muffler being indicated in elevation;

Fig. 2 is an end view of the device; and

Figs. 3 and 4 are sections on lines 3—3 and 4—4 respectively of Fig. 1.

Referring to the drawings, A denotes the exhaust pipe from the engine, B denotes the muffler generally, and C the exhaust from the muffler.

As shown, the muffler comprises an outer casing 10 which is unperforated, and from which leads the muffler exhaust pipe C. Fitted within the outer casing is a sleeve 11 having suitable perforations therein. Preferably the perforations are formed by punching the metal outwardly, leaving a portion of the metal extending in the direction of gas flow, thus serving to direct the flow of gases toward the muffler exhaust. The perforations 12 are provided in the forward end of the sleeve and on the major portion of its circumference, leaving, however, an unperforated portion 13 at the rear end of the

sleeve. The sleeve 11 may be secured to the outer casing by any suitable means 14 well known in the muffler art.

Fitted within the sleeve 11 is an inner sleeve 15 which is materially shorter than the outer sleeve, and is perforated throughout its circumference and also at the forward portion. These perforations designated at 17 are similar to the perforations 12 in the outer sleeve and are designed to direct gases in a forward direction. Preferably the perforations 17 are out of alignment with the perforations 12, so that a thorough mixing of gases will be insured. The sleeve 15 is flanged at its rear end as at 16, and these flanges fit against the outer sleeve. Suitable connections 16' between the inner and outer sleeves are also provided.

The arrangement of the sleeves described above leaves at the rear of the muffler a chamber 18 which is closed at the sides by the unperforated portion 13 of the outer sleeve and partially closed at the forward end by the flange 16. At the rear portion of the chamber 18 there is provided a plate 19 perforated throughout its area as at 20, and centrally apertured to permit the engine exhaust pipe A to pass therethrough. The purpose of the perforations 20 is to permit air to be drawn into the chamber 18 and thence into the muffler by means of the suction produced by the ordinary operation of the muffler.

In operation the exhaust gases enter the space within the inner sleeve 15 through the engine exhaust pipe A, and these gases pass thence through the perforations 17 into the space between the two sleeves, thence into the space between the outer sleeve and the casing, from which they pass outwardly through the muffler exhaust into the atmosphere.

The passage of the exhaust gases produces a suction which draws air from the outside atmosphere through the perforations 20 into the relatively large chamber 18 surrounding the engine exhaust pipe. This air is heated by contact with the exhaust pipe A, and as it is drawn into the inner chamber it becomes mixed with the exhaust gases. Further admixture takes place in passing through the staggered perforations of the muffler, and

at the same time further heating results. The result is that by the time the gases and air pass from the muffler exhaust C, a thorough admixture of the gas and air and the heating of the air has taken place. This gaseous mixture due to the heating of the air is considerably lighter than the cold air outside of the muffler, and as a result the mixture passing from C rises and becomes thoroughly diffused with the outside atmosphere. Moreover, a certain proportion of the heated air has combined with the carbon monoxide within the muffler, and further combination takes place on issuing from the muffler, so that the poisonous effect of the exhaust gases is done away with.

A particular embodiment of the invention has been described in detail for the purpose of illustration, but it will be understood that the invention is not to be limited to such details.

What I claim is:

1. A muffler comprising an outer casing having an exhaust outlet at one end, a sleeve fitted within the outer casing and perforated for the major portion of its length, but having an unperforated portion at the end remote from the muffler exhaust outlet, an inner perforated sleeve spaced from the first-mentioned sleeve and terminating adjacent the beginning of the unperforated portion of the first-mentioned sleeve in a direction away from the exhaust outlet, forming a chamber having an unperforated cylindrical wall extending from the forward end of the inner sleeve to the forward end of the muffler and surrounding the engine exhaust pipe, and an end plate having perforations for the admission of air to said chamber, and having a central opening to permit passage of the engine exhaust pipe.

2. A muffler comprising an outer casing having an exhaust outlet at one end, a sleeve fitted within the outer casing and perforated for the major portion of its length, but having an unperforated portion at the end remote from the muffler exhaust outlet, an inner perforated sleeve spaced from the first-mentioned sleeve and terminating adjacent the beginning of the unperforated portion of the first-mentioned sleeve in a direction away from the exhaust outlet, forming a chamber having an unperforated cylindrical wall extending from the forward end of the inner sleeve to the forward end of the muffler and surrounding the engine exhaust pipe.

3. A muffler comprising an outer casing, having an exhaust inlet at one end and an exhaust outlet at the other, spaced concentric perforated sleeves within the outer casing, the outer of said sleeves having an unperforated portion toward the exhaust inlet, and the inner of said sleeves terminating substantially at said unperforated portion and having an out-turned flange at the end there-

of closely fitting the outer sleeve and forming a chamber having an unperforated cylindrical wall surrounding the exhaust inlet.

4. A muffler comprising an outer casing, having an exhaust inlet at one end and an exhaust outlet at the other, spaced concentric perforated sleeves within the outer casing, the outer of said sleeves having an unperforated portion toward the exhaust inlet, and the inner of said sleeves terminating substantially at said unperforated portion and having an out-turned flange at the end thereof closely fitting the outer sleeve and forming a chamber having an unperforated cylindrical wall surrounding the exhaust inlet, and means for admitting fresh air to said chamber.

In testimony whereof I affix my signature.

CHARLES R. MINER.
